UNITED STATES PATENT OFFICE.

HORACE WILLIAMS AND JOHN L. ALBERGER, OF BUFFALO, NEW YORK.

PROCESS OF MANUFACTURING CRYSTALLIZABLE GRAPE-SUGAR.

SPECIFICATION forming part of Reissued Letters Patent No. 9,850, dated August 23, 1881.
Original No. 241,903, dated May 24, 1881. Application for reissue filed July 23, 1881.

To all whom it may concern:

Be it known that we, HORACE WILLIAMS and JOHN L. ALBERGER, of Buffalo, in the county of Erie and State of New York, have 5 jointly invented a new and Improved Process of Manufacturing Crystallizable Grape-Sugar from Corn or other Cereals, of which the following is a description in such full, clear, concise, and exact terms as to enable any one 10 skilled in the arts to which it is most nearly connected to work or practice the same.

The object of this invention is to eliminate more perfectly the unconverted starch, dextrine, oils, acids, alkali, and all the elements 15 of the grain and process that impart to the crystallized sugar its impurity, bad odor, or flavor; and our said invention consists of the following process of treating the starch, soluble dextrine, sirup, and crystallized sugar, by 20 which the aforesaid object is obtained.

First. We take starch, or soluble dextrine made of starch or grain, and treat it in a vessel of suitable construction, under the action of steam heat, in a solution of acid and water 25 strong enough to convert the starch into dextrine and the dextrine into sirup or sugar-liquor, the treatment to be continued until the conversion is perfected, to be ascertained by the usual test. The solution, if sulphuric acid 30 be used, should be composed of about forty pounds of starch, three-fourths of a pound of acid, and twenty gallons of water, and the heat should be that due to about forty pounds of steam-pressure per square inch of the containing-vessel.

Second. After thus converting the starch and dextrine into sirup, as aforesaid, we neutralize the acid in the sirup with alkali, or any of the well-known neutralizing agents for this 35 purpose, then separate the neutralizing agent by filtering, in the usual way, then decolorize the sirup with bone-black, filtering, or by any other means known to the art, and then boil the sirup in a vacuum-pan to 33° or 35° Baumé, 40 with a temperature of 120° Fahrenheit. To 45 neutralize the acid in the sirup about two per cent. of alkali should be used.

Third. The sirup having been thus purified, decolorized, and reduced, it is drawn into a 50 receiver of suitable construction, where we allow it to cool to the ordinary temperature of the atmosphere. We then proceed to induce

crystallization. This is done by rapidly mixing into the sirup a small percentage—say one per cent.—of finely-powdered grape-sugar, by 55 which there are furnished granules for the crystals to form upon. Now, by allowing the mass to stand quietly for ten or twelve hours, the sugar will crystallize throughout, leaving the mother-liquor free in the receiver. Having 60 reached this stage of the process, the sugar, in crystallizing, separates itself from the impurities of the sirup, and would be pure sugar did not the impurities of the sirup adhere to the outside of the crystals. The final step, 65 then, is to free the crystallized sugar from the mother-liquor or sirup remaining after crystallization. This we do either by putting the crystallized sugar into a centrifugal and throwing out the mother-liquor or remaining sirup, 70 washing it or not in the centrifugal, as may be required, or by putting the crystallized sugar into bags or sacks and expelling the liquor by means of a hydraulic press, leaving within the sacks or centrifugal a pure hard sugar, which 75 may be remelted and worked, or cast in blocks, or ground and pulverized.

A modification of this method is to put the crystallized sugar in a mixer of any suitable construction and mix with it from five to ten 80 per cent. of water reduced to 32° of Fahrenheit, or as near as may be, the object of this cold-water treatment being to wash the crystals without melting them, after which we draw from the mixer into a centrifugal and expel the liquid portions, or we place the mass 85 into bags and press out, as before stated. If the latter method be used, the sugar may be concentrated to a greater degree of gravity—say 37° to 38° Baumé, at 120° Fahrenheit. 90

In this process, if any of the starch or dextrine be left unconverted in any of its steps, the unconverted starch or dextrine will be carried off with the mother-liquor, leaving the sugar pure, the starch or dextrine to be again 95 treated as before.

The sugar produced by this process is of great value in the arts, in which it has a wide range of use, such as sweetening wines, cider, &c., and for making ales or spirituous liquor, 100 and for sweetening table-fruits, &c., the sugar of this process being perfectly pure and free from the usual flavors that characterize the grape-sugar made by the processes now in use.

Having thus described our process, we claim and desire to secure by Letters Patent—

1. The process, substantially herein described, of manufacturing and crystallizing 5 grape-sugar from corn or cereals, consisting of first converting the starch and dextrine into sirup in a solution of acid and water under steam heat, then neutralizing the acid, then separating the neutralizing residuum, then filtering with bone-black, then reducing in a vacuum-pan, then cooling the reduced or concentrated sirup, then adding a small percentage of powdered grape-sugar, then washing the crystallized grape-sugar in cold water, and 15 finally throwing or pressing out the mother-liquor, substantially as described.

2. The process, substantially herein described, of eliminating the impurities of crystallized grape-sugar by pressure or centrifugal force, as set forth.

3. The process, substantially herein described, of washing off and eliminating the impurities of crystallized grape-sugar by pressure or centrifugal force, as set forth.

HORACE WILLIAMS.
JOHN L. ALBERGER.
